UNITED STATES PATENT OFFICE.

GEORGE BEATON, OF SYDNEY, NOVA SCOTIA, CANADA.

BLAST-FURNACE TUYÈRE.

Application filed June 30, 1923. Serial No. 648,736.

To all whom it may concern:

Be it known that I, GEORGE BEATON, a subject of the King of Great Britain, and resident of Sydney, in the Province of Nova Scotia, Dominion of Canada, have invented certain new and useful Improvements in Blast-Furnace Tuyères, of which the following is a specification.

This invention relates to improvements in blast furnace tuyères, and has for its primary object to provide a tuyère nose carrying a covering of refractory material.

Further objects are to provide a tuyère nose which is to be provided with a protector of refractory material at the lower side, which is nearest to the hearth of the furnace.

Other objects also are to provide a tuyère which will have its nose provided with an annular covering of refractory material designed to replace the old style of tuyères, which were burning on the upper and lower edge of the nozzle.

A further object is the provision of a tuyère for blast furnaces that will not quickly burn up and thus obviate the necessity of having, as is the case with tuyères at present in use, to frequently shut off the blast for ten or fifteen minutes while a burnt out tuyère is being replaced. It is a known fact that in blast furnaces a great number of tuyères are burnt up even in the space of a month under present conditions, and to remedy this frequent replacing of tuyères is an essential object of my invention.

Only one of the improved tuyères is burnt out per week, so that the invention has a decided effect on the efficiency of the furnace, the cost of running of which is considerably lowered.

Further objects are to provide an improved blast furnace tuyère that is simple in construction, not liable to go out of repair, and generally to adapt the several parts to better perform the functions required of them.

In the drawings:—

Figure 1 is a plan view of the improved tuyère.

Figure 2 is a longitudinal section.

Figure 3 is a longitudinal section through a somewhat modified form of tuyère.

Figure 4 is a bottom plan view of the tuyère.

Figure 5 is a bottom plan view of the tuyère shown in Figure 3.

Figure 6 is an enlarged sectional detail view taken on the line 6—6 of Figure 1.

Figure 7 is a plan view of an alternative form of tuyère.

Figure 8 is a longitudinal section.

Figure 9 is a longitudinal section showing an annular refractory block.

Figure 10 is a bottom plan view of the tuyère shown in Figure 8.

Figure 11 is a bottom plan view of the tuyère shown in Figure 9.

Like characters of reference indicate corresponding parts in all the figures.

Referring more in particular to drawings for a detailed description, A represents the tuyère, which may be cast of any suitable metal, and is of the usual construction, comprising the tapering cylindrical body 10 formed with the annular water jacket 11. A water inlet 12 and a water outlet 13 are provided, as shown in Figures 1 and 7.

Connected to the water inlet 12 is a metallic pipe 14, which is coiled within the annular jacket 11, and leads the water to the inner part of the tuyère.

The tuyère nose 15 is cored out as at 16 in order to form an arcuate recess on the side of the tuyère, which is to be lowermost in the furnace, and nearest the hearth. This particular construction is designed to replace the old style of tuyère, which were burning on the lower edge of the nozzle.

In order to protect the tuyère, a filling of refractory material 17 is placed within the recess 16, and the refractory material may be securely held within the recess by means of dove-tailed projections or studs 18 provided in the bottom of the recess.

In order to place this refractory material within the recess, the tuyère nose is cored as already explained in order to provide the recess 16, and the refractory is rammed within the recess as hard as possible. The tuyère is then placed nose down on a smooth plate and left in an ordinary foundry core oven for a period of about forty-eight hours, more or less. The thin ring of metal left on the outside diameter of the nose will protect the refractory from abuse in shipping and rough handling at the furnace.

In case a vitrified refractory is used, it can

be cast in the nose of the tuyère and kept from shrinking by casting narrow slots in the thin ring of metal as shown at 19 in Figures 2 to 5 inclusive. In other words, these slots cored in the thin metal around the nose are designed to prevent the tearing of the casting while shrinking on the hard refractory core.

The refractory may be any material such as carborundum, carbon, refrax, silfrax, carbofrax, silica, dolomite, lime, fireclay, crome, zirconia, magnesia, beuile, quarzite or any other known refractory used singly or mixed with another and bonded with any bonding material whatsoever such as; tar, pitch, refractory clay and sodium silicate, carborundum cements, etc. So far the best refractory obtained has been made by a mixture of magnesia bonded with carborundum cement.

With reference to the composition of the materials above referred to, refrax and silfrax are two products made by a special process of recrystallization and are composed wholly of carborundum, held in solid form by the interlocking and inter-growth of silicon carbide crystals. The chief differences between these two products is in the size of the crystalline particles, "silfrax" being composed of extremely fine carborundum powder and "refrax" of coarser particles. "Refrax" is composed wholly of carborundum held together by crystallization and, therefore, has the properties of silicon carbide, unaltered by any bonding agent.

"Carbofrax" may be termed the best known type of carborundum refractory and is composed of crystals of silicon carbide held together by a small percentage of a bonding refractory material. Three varieties of this type are produced and known as carbofrax "A," carbofrax "B" and carbofrax "C." Carbofrax is made not only in standard refractory shapes but also moulded into more or less intricate forms as required for special applications. On account of the small amount of bonding material used, "carbofrax" has most of the properties of carborundum itself.

"Crome" analyzes as follows:

	Per cent.
Chromium	38 to 40
Alumina	24.5
Iron peroxide	17.5
Silica	3.25
Magnesia	15

"Bauxite" or "Beuile" is a hydrous oxide of alumina and analyzes approximately as follows:

	Per cent.
Silica	4 to 7
Iron peroxide	3 to 5
Alumina	90

In order to replace a tuyère which burns on both the top and bottom, the cored out

recess 16 may be in the form shown at 20 forming an annular recess having an inclined bottom 21, so that a heavier thickness of refractory may be placed at the bottom, which is nearest the hearth of the furnace, than at the top, where the temperature to which the tuyère is submitted is not so intense.

If desired also, the means of retaining the refractory within the recess instead of comprising studs as shown in Figures 2 to 5, may consist of dove-tailed transverse pieces or projections 22, which extend radially within the recess 20.

It will be obvious that this improved tuyère has considerable advantages over the metallic tuyère now used, and that having an average life of twelve weeks as compared to the exceedingly shorter life of the present tuyère, which is burnt at the rate of 10 a day, it will have a decided effect on the efficiency of the furnace, since the blast not being taken off so often, the temperature will be kept up better than heretofore, with the result that the output of the furnace will be greater.

As many changes could be made in the above construction, and many apparently widely different embodiments of my invention, within the scope of the claims, constructed without departing from the spirit or scope thereof, it is intended that all matter contained in the accompanying specification and drawings shall be interpreted as illustrative, and not in a limiting sense.

What I claim as my invention is:

1. A blast furnace tuyère comprising a cylindrical body portion, an annular water jacket in the body portion, the body portion being formed with a cored out recess in the nose, and a filling of refractory material in the recessed nose.

2. A blast furnace tuyère comprising a cylindrical body portion, an annular water jacket in the body portion, the body portion being formed with a cored out annular recess in the nose, and a filling of refractory material in the recessed nose.

3. A blast furnace tuyère comprising a cylindrical body portion, an annular water jacket in the body portion, the body portion being formed with a cored out annular recess in the nose, the bottom of the recess being inclined, and a filling of refractory material in the recessed nose.

4. A blast furnace tuyère comprising a cylindrical body portion, an annular water jacket in the body portion, the nose of the body portion being formed with a recess on the side to be nearest the hearth of the furnace, and a filling of refractory material in the recess.

5. A blast furnace tuyère comprising a cylindrical body portion, an annular water jacket in the body portion, the body portion

- nose being formed with an annular recess, and a filling of refractory material in the recess, the refractory being heavier on the side nearest the hearth of the furnace.
5. 6. A blast furnace tuyère comprising a cylindrical body portion, an annular water jacket in the body portion, a spiral type within the water jacket, conducting the water to the hottest part of the tuyère, the body portion being formed with a cored out recess in the nose, and a filling of refractory material in the recessed nose.
7. The method of forming a blast furnace tuyère, which consists of applying a refractory material on the nose of the tuyère, then placing the tuyère, nose down, on a smooth surface in an ordinary foundry core oven and subjecting the core to a baking treatment for a predetermined period, the weight of 20 the tuyère being utilized to retain the rammed refractory in a solid body.
8. A blast furnace tuyère comprising a cylindrical body portion, an annular water jacket in the body portion, the body portion nose being formed with a recess, a fill-
- ing of refractory material in the recess, the recess walls being slotted, as and for the purpose specified.
9. A blast furnace tuyère comprising a cylindrical body portion, an annular water jacket in the body portion, the body portion being formed with a cored out recess in the nose, a filling of refractory material in the recessed nose, and a plurality of dove-tailed projections cast in the bottom of the recess to retain the refractory.
10. A blast furnace tuyère comprising a cylindrical body portion, an annular water jacket in the body portion, a spirally wound pipe in the jacket, the body portion nose being formed with an annular recess, dove-tailed projections in the bottom of the recess, and a filling of refractory material retained in the recess by the projections.

In witness whereof I have hereunto set my hand in the presence of two witnesses.

GEORGE BEATON.
